(57) **CLAIM**

The ornamental design of a coating film transfer apparatus, as is shown and described.

DESCRIPTION

The subject invention is directed to the ornamental design of a coating film transfer apparatus for applying an adhesive film or correction film to a substrate surface, as shown and described in the accompanying drawings, wherein portions of the coating film transfer apparatus shown in broken lines form no part of the claimed design, wherein:

FIG. 1 is a front view of the coating film transfer apparatus of the subject invention;

FIG. 2 is a rear view of the coating film transfer apparatus of the subject invention;

FIG. 3 is a top view of the coating film transfer apparatus of the subject invention;

FIG. 4 is a bottom view of the coating film transfer apparatus of the subject invention;

FIG. 5 is a left side view of the coating film transfer apparatus of the subject invention;

FIG. 6 is a right side view of the coating film transfer apparatus of the subject invention; and,

FIG. 7 is a perspective view of the coating film transfer apparatus of the subject invention.
